UNITED STATES PATENT OFFICE.

JAMES F. FREEMAN, OF LAWRENCE, MASSACHUSETTS

MACHINE FOR CLEANING BRICKS.

Specification of Letters Patent. Patented July 23, 1912.

1,033,573.

Application filed February 28, 1912. Serial No. 678,760.

To all whom it may concern:

Be it known that I, JAMES F. FREEMAN, a citizen of the United States, and a resident of Lawrence, in the county of Essex and State of Massachusetts, have invented certain new and useful improvements in Machines for Cleaning Bricks, of which the following is a specification:

This invention relates to machines for removing mortar, etc., from bricks which have once been used, in order that the bricks may be again used for building purposes.

The invention has for its object to provide a simple and effective machine adapted to rapidly clean the surfaces of old bricks and it consists in the improvements which I will now proceed to describe and claim.

Of the accompanying drawings:—Figure 1 represents a side elevation of a brick cleaning machine embodying my invention. Fig. 2 represents a top plan view of the same. Fig. 3 represents a side view of a portion of one of the cutter-carrying heads. Fig. 4 represents a section on line 4—4 of Fig. 3. Fig. 5 represents a perspective view of one of the loose rotary cutters hereinafter described. Fig. 6 represents a section on line 6—6 of Fig. 3.

The same reference characters indicate the same parts in all the figures.

In the drawings:—12 represents a supporting frame which is preferably portable and mounted on wheels 13. 14 represents a shaft journaled in bearings 15 on the frame. 16 represents a head having a hub 17 rigidly attached to the shaft 14, the head being preferably a disk having an outer face arranged in a plane substantially at right angles with the shaft 14.

18 The head 16 is provided with a plurality of slots 18, said slots being preferably arranged in radial rows, as indicated by Figs. 1 and 3. Through said slots project circular serrated cutters 19 which are mounted to rotate loosely on axes substantially at right angles with the axis of rotation of the head, the cutters being arranged in rows corresponding to the rows of slots, and each row of cutters being preferably mounted to rotate loosely on a stud 20 affixed to the head 16. The studs 20 are radially arranged and each is preferably

screw-threaded at its inner end portion, as shown by Fig. 4, and screwed into a threaded orifice in the hub 17, the outer end of the stud being located in an orifice in a flange 21 formed on the head 16, as shown by Fig. 4. The studs are therefore removable from the cutters, which are formed to substantially fill the width of the slots so that when a shaft is removed the accompanying cutters are left loose in the slots and may be readily withdrawn therefrom. The cutters on each shaft are spaced apart by the portions of the heads between the slots so that in assembling the parts the cutters may be first inserted loosely in the slots, and the shafts then passed through the cutters and secured. Provision is thus made for readily applying and removing the cutters.

The shaft 14 and head 16 are rotated by any suitable means, preferably in the direction indicated by the arrow in Fig. 1.

A brick to be cleaned is placed by the operator on a horizontal shelf 22 attached to the frame 12, the upper surface of said shelf being preferably substantially radial to the axis of the shaft 14, as shown by Fig. 1. The operator presses the brick toward the outer side of the head 16 and the cutters 19 of each row approaching the shelf 22, are brought successively into contact with the inner face of the brick and caused to rotate by their contact with the brick. The teeth of the cutters therefore act as chisels to dislodge mortar adhering to the brick. The cutters of the successive rows are preferably staggered, as shown by Figs. 1 and 3, so the cutters of each row act upon portions of the brick between those acted on by the preceding row, so that the operator by pressing the brick toward the outer face of the head and without moving it endwise is enabled to cause the denudation of substantially the entire inner face of the brick. The outer face of the head arranged as stated at right angles with the axis of rotation of the head, acts as a stop to limit the entrance of a brick into the spaces between the axes of the rows of cutters, said stop being formed by the portions of the said face intervening between the cutters. It is not possible therefore to insert a corner of a brick so far

between the axes of the rows of cutters as to incur liability of breakage of said corner by the cutters. If this stop were not provided, the operator might carelessly force 5 one end or corner of a brick inwardly so far that it would receive a crushing blow from an approaching cutter or cutters. The radial arrangement of the upper surface of the shelf relatively to the axis of the head, 10 causes each row of cutters to approach and cross the shelf with its axis substantially parallel with the shelf, so that the cutters roll easily across the inner face of a brick without scraping and without being pressed 15 sidewise against the walls of the slots in the head. The rolling contact of the cutters with the material on which they act reduces to the minimum the wear of the cutter teeth, there being no such wear as would be caused 20 by a scraping movement of the teeth in contact with the material. The absence of sidewise pressure of the acting cutters on the walls of the slots, reduces to the minimum not only the frictional resistance to the rotation 25 of the cutters (so that their teeth have no tendency to scrape) but also the power required to rotate the head.

I prefer to make each cutter by stamping it from a relatively thin sheet of steel, and 30 to provide two cutters for each slot, although, if desired, the thickness of each cutter may be sufficient to substantially fill its slot, as indicated by Fig. 5.

The shelf 22 may be adjustable toward 35 and from the outer face of the head 16, and as here shown, the shelf is provided with an arm 23 having a slot 24 through which passes an attaching bolt 25, the slot and bolt permitting the described adjustment of 40 the shelf.

26 represents a hood which partially incloses the head 16 and communicates with a fan casing 27 in which is located a rotary suction fan 28 mounted on a shaft 29 which 45 is journaled in bearings 30 on the frame 12. The rotation of the fan 28 draws a current of air through the hood 26, the air carrying the dust raised by the cutters and discharging it through a flue 31 communicating 50 with the fan casing.

The shafts 14 and 29 are preferably rotated in unison by a suitable motor 32 mounted on the frame, the shaft of the motor being provided with a driving pulley 55 33, connected by a belt 34 with a pulley 35 on the shaft 14. A pulley 36 on the shaft 14 is connected by a belt 37 with a pulley 38 on the shaft 29. It is obvious that any other suitable driving connection may be 60 provided between the motor and the head 16 and fan 28.

The machine may be provided with two heads 16, located at opposite ends of the

shaft 14, the shelf 22, hood 26 and suction fan 28 being duplicated, as shown by Fig. 2. 65

I claim:

1. A brick cleaning machine comprising a rotary head having an outer face arranged in a plane substantially at right angles to the axis of the head, and numerous spaced slots arranged in substantially radial rows, all the slots being separated from each other by intervening portions of said head, studs attached to the head behind said face, each stud extending across a row of slots, rows of serrated cutters mounted to rotate loosely on said studs and projecting into said slots, some of the teeth of each cutter projecting outwardly from said face to have a rolling engagement with an accumulation of mortar on a brick pressed toward the face, and a brick-supporting shelf adjacent to the head, the portions of the outer face of the head between the slots serving as a stop to limit the movement of a brick into the spaces between the axes of the cutters.

2. A brick cleaning machine comprising a rotary head having an outer face arranged in a plane substantially at right angles to the axis of the head, and numerous spaced slots arranged in substantially radial rows, all the slots being separated from each other by intervening portions of said head, studs attached to the head behind said face, each stud extending across a row of slots, rows of serrated cutters mounted to rotate loosely on said studs and projecting into said slots, some of the teeth of each cutter projecting outwardly from said face to have a rolling engagement with an accumulation of mortar on a brick pressed toward the face, the portions of the outer face of the head between the slots serving as a stop to limit the movement of a brick into the spaces between the axes of the cutters, and a fixed brick-supporting shelf adjacent to said outer face and having a supporting surface arranged substantially radial to the axis of the head whereby the cutters of each row approaching the shelf are caused to roll across the inner face of a brick supported thereby with the minimum of frictional resistance and wear, the cutters of each row being staggered relatively to the cutters of the adjacent rows.

3. A brick cleaning machine comprising a rotary head having a face substantially at right angles with its axis of rotation, said head having slots arranged in radial rows, and a corresponding series of radially arranged studs removably attached to the head behind the series of slots and extending across the slots, and serrated circular cutters mounted to rotate loosely on said studs and projecting through the slots, the cutters be-

ing formed to substantially fill the width of the slots and being spaced apart on the studs by the portions of the head between the slots, and the studs being removable from the spaced cutters to leave the cutters loose in the slots and permit their removal from the head.

In testimony whereof I have affixed my signature, in presence of two witnesses.
